ATTORNEY

UNITED STATES PATENT OFFICE.

WILLIAM SCHMIDBAUER, OF SILVERTON, OREGON.

PORATABLE CIRCULAR SAW.

1,291,181.

Specification of Letters Patent. Patented Jan. 14, 1919.

Application filed June 20, 1918. Serial No. 241,025.

To all whom it may concern:

Be it known that I, WILLIAM SCHMIDBAUER, a citizen of the United States, residing at Silverton, in the county of Marion 5 and State of Oregon, have invented certain new and useful Improvements in Portable Circular Saws, of which the following is a specification.

This invention relates to improvements in 10 portable circular saws.

One object of this invention is the production of a portable motor saw wherein the driving mechanism is carried within a casing upon which the motor is carried, and a 15 saw is driven by the driving mechanism and extends to an operative position beyond the outer portion of the casing.

Another object of this invention is the production of a motor saw, wherein a portion 20 of the saw is guarded to prevent injury to the operator, the casing also being provided with a partition for preventing the saw dust from flying into the driving gears.

Another object of this invention is the 25 production of a motor saw including a casing which is provided with a removable wall, thus facilitating the removal of the saw for sharpening or for permitting the placing of another saw in an operative position when necessary.

One practical form of construction and assembly of the present invention will be 30 hereinafter described, and is illustrated in the accompanying drawing, in which—

Figure 1 is a front elevation of the portable motor saw, and Fig. 2 is a central vertical section through the device.

In the preferred embodiment of the present invention, about to be described, it will 40 be seen that the casing 5 comprises a bowed rear wall 6 and a partition 7. The partition 7 is substantially parallel to the rear wall 6. The annular wall 8 extends from the partition 7 and is fixed in any desired manner 45 upon the rear wall 6, thus forming an enclosed compartment. The motor, which is indicated in general at 9 is fixed by bolts 10 upon the outer surface of the rear wall 6 and may be controlled by the switch 11 50 which is also carried upon the outer surface of the rear wall. The electric conductors 12 are connected to the motor and to the switch for supplying the motor with the necessary electric current for operating the same. The 55 armature shaft 13 of the motor 9 extends through the rear wall 6 and through the enclosed compartment and has its forward end

journalized in a bearing 14 formed in the partition 7.

An enlarged driving gear 15 is keyed upon 60 the shaft 13 and is carried within the inclosed compartment. The shaft 16 is carried by the rear wall 6, the partition 7 and removable front wall to be hereinafter referred to. The reduced gear 17 is keyed upon the 65 shaft 16 and meshes with the enlarged driving gear 15. Therefore when the motor is in operation and the shaft 13 is rotating, the enlarged driving gear 15 will rotate and in turn impart rotary motion through the gear 70 17 to the shaft 16.

A fixed front wall 18 is formed on the casing at the junction of the partition 7 and the annular wall 8 and is bowed outwardly to form a hood-like structure. This front 75 wall has a curved flanged edge 19.

The removable front wall 20 has ears 21 formed thereon through which the retaining elements 22 are passed for fixing the front wall 20 upon the front wall 18. It should 80 be noted that the edge of the removable wall 20 engages the flange 19, which forms an abutment for steadyng or reinforcing the removable wall 20. This removable wall 20 is provided with a bearing 23 in which the 85 forward end of the shaft 15 removably fits.

The circular saw 24 is removably keyed upon the shaft 16 and extends between the partition and the removable wall 20. Therefore, it is obvious that as the shaft 16 is rotated, rotary motion will be imparted to the saw 24. As the saw extends for considerable distance beyond the casing, it is obvious 90 it may be placed in engagement with articles to be sawed and owing to the rotary motion 95 of the saw, this operation will be easily performed.

In order to support the saw casing, the handle 25 is formed or fixed upon the annular wall 8, while a grip 26 is fixed upon 100 the removable wall 20.

When so desired, the retaining elements 23 may be removed and thus permit the removable front wall 20 to be removed from engagement with the fixed front wall 18 and 105 the flange 19 thereof. As the bearing 23 disengages the front end of the shaft 16, it is obvious the saw 24 may also be removed from engagement with the shaft 16. Accordingly, the saw may be sharpened or if 110 so desired may be replaced by another saw. After this operation, the bearing 23 may be again slipped over the front end of the shaft 16 for constituting a support therefor and

also for holding the saw against displacement.

It will be noted that the partition 7 will prevent the saw dust thrown from the teeth 5 of the saw from flying onto the gears carried within the casing and interfering with the operation thereof. The hood and the removable wall also protect portions of the saw edge which are not necessary in operation 10 and for this reason need not be exposed. However, as the hood of the casing is open at its lower portion, the saw dust will very quickly fall therefrom.

The foregoing description and the drawings have reference to what may be considered the preferred, or approved, form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by 25 Letters Patent, is—

1. In a device of the class described, the combination of a casing, said casing including a rear wall, a partition extending substantially parallel to the rear wall, an annular wall 30 formed upon the partition and connected to the rear wall, a motor fixed upon the outer portion of said rear wall, said motor having a shaft extending therefrom and carried by said rear wall and said partition, a gear keyed upon said shaft, a second shaft 35 carried by said wall and said partition, a gear keyed upon the last mentioned shaft and meshing with the first mentioned gear, whereby when the first mentioned gear is rotated, rotary motion will be imparted through the last mentioned gear to said second mentioned shaft, and a saw keyed upon the last mentioned shaft to be rotated therewith.

2. In a device of the class described, the combination of a casing including an inclosed compartment, gears rotatably mounted within said compartment, means for driving said gears, a fixed front wall 40 constituting a hood like structure for the forward portions of said casing, said front wall having a bearing flange thereon, a removable wall engaging the bearing flange to be held steadily, means for holding the removable wall against accidental displacement, a shaft connected to one of said driving gears and extending from the inclosed compartment and being carried by said removable wall, and a saw removably keyed 45 upon said shaft, said saw extending beyond the outer portion of said casing.

3. In a device of the class described, the combination of a casing consisting of a rear

wall, a partition extending substantially parallel to the rear wall, an annular wall 65 formed on the partition and connected to said rear wall, thus constituting an inclosed compartment, a motor fixed upon the outer portion of the rear wall, a shaft extending from the motor and carried by the rear wall, and said partition, a gear keyed upon said shaft, between the rear wall and partition, a second shaft carried by said wall and partition, a gear keyed thereon and meshing with the first mentioned gear, whereby when the 70 motor is running rotary motion will be imparted through said gears to the last mentioned shaft, a front fixed wall extending from the partition, said front fixed wall having a flange thereon, a removable front wall 75 carried by said flange, means for holding the removable wall in a set position, said last mentioned shaft also being journaled in the removable wall, a saw keyed upon said shaft between the partition and the removable 80 wall, said saw extending beyond the casing, and supporting elements carried upon said annular wall and said removable wall.

4. In a device of the class described, the combination of a supporting means, driving means carried by said supporting means, a hood like wall carried by said supporting means, a saw removably carried by said supporting means and being actuated by said driving means, and a removable wall mounted upon said hood-like wall, said removable wall constituting a guard for a portion of said saw, and also holding the saw in an operative position.

5. In a device of the class described, the combination of a casing including a partition and a front wall, driving means carried by said casing, a saw supported by said casing and being actuated by said driving means, a removable wall releasably connected to 100 said front wall for constituting a guard for said saw and also holding said saw in position.

6. In a device of the class described, the combination of a casing including a partition and a flanged front wall, driving means carried within said casing and having a shaft extending beyond the partition, a saw removably carried upon said shaft, and a removable wall engaging the flanged front 110 wall of said casing for supporting said shaft, for releasably holding said saw in an operative position and at the same time guarding a portion of the saw.

In testimony whereof I affix my signature 120 in presence of two witnesses.

WILLIAM SCHMIDBAUER.
